(57) **CLAIM**

The ornamental design for a connector, as shown and described.

DESCRIPTION

FIG. 1 is a top and side perspective view of a connector; FIG. 2 is a bottom and side perspective view thereof; FIG. 3 is a top view thereof; FIG. 4 is a bottom view thereof; FIG. 5 is a first side view thereof; FIG. 6 is a second side view thereof; FIG. 7 is a front view thereof; and, FIG. 8 is a back view thereof.

Broken lines are used to illustrate portions of the connector or environmental subject matter that form no part of the claimed design. The dot-dash-dot and/or the diagonal shaped group of lines form the bounds of the claimed design and are not part of the claimed design.
